US00D555377S

(12) **United States Design Patent** (10) **Patent No.:** **US D555,377 S**
Pensi et al. (45) **Date of Patent:** **** Nov. 20, 2007**

(54) **SEATING UNIT**

(75) Inventors: **Jorge Pensi**, Barcelona (ES); **James N. Ludwig**, Grand Rapids, MI (US); **Gordon J. Peterson**, Rockford, MI (US); **Bruce M. Smith**, Grand Rapids, MI (US); **Terence Sean Yoo**, Grand Rapids, MI (US); **Kurt R. Heidmann**, Grand Rapids, MI (US)

(73) Assignee: **Steelcase Development Corporation**, Caledonia, MI (US)

(**) Term: **14 Years**

(21) Appl. No.: **29/254,521**

(22) Filed: **Feb. 24, 2006**

(51) **LOC (8) Cl.** **06-01**

(52) **U.S. Cl.** **D6/366**

(58) **Field of Classification Search** D6/334-335, D6/356, 364, 365-367, 368, 374, 379, 498, D6/500-502; 297/232, 411.27, 452.21, 452.29, 297/452.32, 452.35, 452.37, 452.48

See application file for complete search history.

CLAIM

We claim the ornamental design for seating unit, as shown.

DESCRIPTION

FIG. 1 is a perspective view of a first embodiment of a seating unit embodying the present invention;

FIG. 2 is a front view of the seating unit shown in FIG. 1; FIG. 3 is a right side view of the seating unit shown in FIG. 1, the left side being a mirror image thereof; FIG. 4 is a rear view of the seating unit shown in FIG. 1; FIG. 5 is a top view of the seating unit shown in FIG. 1; and FIG. 6 is a bottom view of the seating unit shown in FIG. 1. FIG. 7 is a perspective view of a second embodiment of a seating unit embodying the present invention; FIG. 8 is a front view of the seating unit shown in FIG. 7; FIG. 9 is a right side view of the seating unit shown in FIG. 7, the left side being a mirror image thereof; FIG. 10 is a rear view of the seating unit shown in FIG. 7; FIG. 11 is a top view of the seating unit shown in FIG. 7; and FIG. 12 is a bottom view of the seating unit shown in FIG. 7. FIG. 13 is a perspective view of a third embodiment of a seating unit embodying the present invention; FIG. 14 is a front view of the seating unit shown in FIG. 13; FIG. 15 is a right side view of the seating unit shown in FIG. 13, the left side being a mirror image thereof; FIG. 16 is a rear view of the seating unit shown in FIG. 13; FIG. 17 is a top view of the seating unit shown in FIG. 13; and FIG. 18 is a bottom view of the seating unit shown in FIG. 13. FIG. 19 is a perspective view of a fourth embodiment of a seating unit embodying the present invention; FIG. 20 is a front view of the seating unit shown in FIG. 19; FIG. 21 is a right side view of the seating unit shown in FIG. 19, the left side being a mirror image thereof; FIG. 22 is a rear view of the seating unit shown in FIG. 19; FIG. 23 is a top view of the seating unit shown in FIG. 19; and FIG. 24 is a bottom view of the seating unit shown in FIG. 19. FIG. 25 is a perspective view of a fifth embodiment of a seating unit embodying the present invention; FIG. 26 is a front view of the seating unit shown in FIG. 25; FIG. 27 is a right side view of the seating unit shown in FIG. 25, the left side being a mirror image thereof; FIG. 28 is a rear view of the seating unit shown in FIG. 25; FIG. 29 is a top view of the seating unit shown in FIG. 25; and, FIG. 30 is a bottom view of the seating unit shown in FIG. 25.
